US00D785562S

(12) **United States Design Patent** (10) Patent No.: **US D785,562 S**
(45) Date of Patent: ** *May 2, 2017

(54) **BATTERY PACK**

(71) Applicant: **BLACK & DECKER INC.**, Newark, DE (US)

(72) Inventor: **Joseph B. Cooper**, Baltimore, MD (US)

(73) Assignee: **Black & Decker Inc.**, New Britain, CT (US)

(*) Notice: This patent is subject to a terminal disclaimer.

(**) Term: **14 Years**

(21) Appl. No.: **29/520,528**

(22) Filed: **Mar. 16, 2015**

(51) LOC (10) Cl. **13-02**

(52) U.S. Cl.

USPC **D13/103**

CLAIM

The ornamental design for a battery pack, as shown and described.

DESCRIPTION

FIG. 1 is a front perspective view of a battery pack showing my new design;

FIG. 2 is a left side view thereof;

FIG. 3 is a right view thereof;

FIG. 4 is a front view thereof;

FIG. 5 is a rear view thereof;

FIG. 6 is a top plan view thereof; and,

FIG. 7 is a bottom plan view thereof.

(Continued)

The broken lines shown in the drawings represent unclaimed portions of the battery pack and form no part of the claimed design.
